UNITED STATES PATENT OFFICE.

EMMETT W. STULL, OF NORWOOD, OHIO, ASSIGNOR TO ALLEN-CHALMERS COMPANY, A CORPORATION OF NEW JERSEY, AND THE BULLOCK ELECTRIC MANUFACTURING COMPANY, A CORPORATION OF OHIO.

MOTOR-CONTROLLER.

No. 852,468.

Specification of Letters Patent.

Patented May 7, 1907.

Application filed July 30, 1906. Serial No. 328,336.

To all whom it may concern:

Be it known that I, EMMETT W. STULL, a citizen of the United States, residing at Norwood, in the county of Hamilton and State of Ohio, have invented certain new and useful Improvements in Motor-Controllers, of which the following is a full, clear, and exact specification.

My invention relates to electric controllers and especially to railway controllers of the series-parallel type.

The object of my invention is to provide a controller by which the motors may be controlled in a number of different ways and arranged so that the "full on" position of the controller under different circumstances may give different speeds of the motors, thus enabling the system to be used for combined city and suburban traffic.

Another object of my invention is to provide for the cutting out of certain disabled motors without in any way varying the control of the other motor or motors or changing their connections with the controller.

To these ends my invention consists broadly of a controller comprising a plurality of drums geared to operate together, each drum being arranged to independently control one or more motors, and a switch arranged to connect said drums and the motors controlled thereby in series or in parallel.

In another aspect my invention consists of a controller comprising a plurality of drums geared to operate together, each drum being arranged to independently control one or more motors, and a switch arranged to cut out any drum and its associated motors.

Other features of my invention will appear from the specification and drawings and will be particularly pointed out in the claims.

Figure 1 is a front elevation of a part of a controller embodying my invention, with the controller casing in section; Fig. 2 is a partial plan view of the controller shown in Fig. 1 with the controller cover partly broken away; and, Fig. 3 is a diagram of the electrical connections, the connections to the reversing switch being omitted in order to simplify the diagram.

In the drawings A and B are two controller drums connected, as by the gear wheels 10 and 11, to be simultaneously operated in opposite directions by the single handle 12.

The handle 12 may be arranged as usual so that it can be removed only when the controller is in "off" position. The drums A and B may be of any desired type and are here shown as series-parallel drums, the drum A controlling the motors 1 and 2 through series and parallel positions, while the drum B controls the motors 3 and 4 in the same way. Each of these controllers has its own set of resistances 13 and 14 respectively, and blow-out coils, 15 and 16 respectively. The usual reversing switch C is provided and is interlocked with the drum B by means of the disk 17, notch-plate 18, and swinging lever 19 so that it can be moved only when the drum B is in "off" position. The connections of the reversing switch are the usual ones and are omitted from the diagram of connections (Fig. 3) in order to simplify the latter.

Adjacent to the drum A is another drum type switch D. This switch is interlocked with the drum A, by means of the disk 20, notch-plate 21, and swinging lever 22 so that it can be moved only when the drum A is in "off" position. The switch D has four operative positions, as indicated in Fig. 3. In the position marked series, it connects the two drums A and B and their associated motors in series with each other, the drums A and B respectively controlling the series or parallel connections of the motors 1 and 2, and 3 and 4. When the drum D is in the position marked "multiple," the drums A and B with their associated motors are in multiple with each other, each of the drums A and B however controlling the individual connections of the motors under its control.

The two positions of the drum D which have just been described are the inner or middle positions of said drum. In one of its extreme positions, marked "A out," the drum A and the motors 1 and 2 controlled thereby are cut out. In the other extreme position, marked "B out," the drum B and the motors 3 and 4 controlled thereby are cut out.

The drums C and D are independently operable by the same removable handle 23. This handle 23 can be moved from the shaft of the drum C only when said drum is in its middle or "off" position as usual. However, it can be removed from the shaft of drum D in any one of the four operative positions of the latter. In the drawings the

handle 23 is shown on the shaft of drum D. Since the two extreme positions of the drum D are only to be used in emergencies, as because of the disabling of one of the motors, 5 stops 24 are provided in the path of the finger 25 on handle 23 so that when the handle 23 is fully in position on the shaft of drum D, said stops 24 and finger 25 prevent movement of the drum into either of its extreme 10 positions. In order to move the drum into these extreme positions the handle 23 must be raised slightly, as will be seen from Fig. 1, so that the finger 25 will clear the stops 24. This prevents the inadvertent movement of 15 the drum D into its extreme positions. The drum D thus provides for the connection of the drum A and B in series for slow speed city traffic, and in parallel for high speed suburban or interurban traffic, and also provides 20 for the cutting out of either drum and its connected motors in case such cutting out should be necessary for any reason. When either drum is cut out, it and its motors are entirely disconnected, while the connections 25 of the other drum and its associated motors are not affected in the slightest. By reason of the interlocks and the use of the same handle for the drums C and D, the drum D can be moved only when the main controller 30 drums A and B and the reversing switch C are in their "off" positions.

I do not wish to be limited to the exact structure here shown and described but intend to cover in the following claims all these obvious modifications and substitutions which will be obvious to one skilled in the art and which come within the spirit and scope of my invention.

What I claim as new and desire to secure 40 by Letters Patent is:—

1. In a controller, a plurality of regulating switches, a motor under the control of each of said switches, and another switch arranged to connect the aforementioned switches and the motors controlled thereby in series and in multiple.

2. In a controller, a plurality of drums, each drum arranged to control one or more motors, and a switch arranged to connect 50 said drums and their associated motors in series and in parallel.

3. In a controller, a plurality of regulating switches, a motor under the control of each of said switches, another switch arranged to connect the aforementioned switches and the motors controlled thereby in series and in multiple, and interlocking mechanism for preventing the movement of said last mentioned switch except when the first mentioned switches are in "off" position.

4. In a controller, a plurality of drums, each drum arranged to control one or more motors, a switch arranged to connect said drums and their associated motors in series 65 and in parallel, and interlocking mechanism

for preventing the movement of said last mentioned switch save when the drums are in "off" position.

5. In a controller, a plurality of regulating switches connected to operate together, a motor under the independent control of each of said switches, and another switch arranged to cut out any one of said first mentioned switches and the motor controlled thereby.

6. In a controller, a plurality of regulating 75 switches connected to operate together, a motor under the independent control of each of said switches, another switch arranged to cut out any one of said first mentioned switches and the motor controlled thereby, so and interlocking mechanism for preventing the movement of said last mentioned switch except when the first mentioned switches are all in "off" position.

7. In a controller, a plurality of drums 85 connected to operate together, each of said drums being connected and arranged to independently control one or more motors, and a switch arranged to cut out any one of said drums and the motor or motors controlled 90 thereby.

8. In a controller, a plurality of drums connected to operate together, each of said drums being connected and arranged to independently control one or more motors, a 95 switch arranged to cut out any one of said drums and the motor or motors controlled thereby, and interlocking mechanism for preventing movement of said switch except when said drums are in "off" position. 100

9. In combination, a plurality of regulating switches, one or more motors under the control of each of said switches, and another switch arranged to connect said first mentioned switches and their associated motors 105 in series and in parallel and to cut out any one of said first mentioned switches and the motor or motors controlled thereby.

10. In combination, a plurality of regulating switches, one or more motors under the control of each of said switches, another switch arranged to connect said first mentioned switches and their associated motors in series and in parallel and to cut out any 110 one of said first mentioned switches and the motor or motors controlled thereby, and interlocking mechanism for preventing the movement of said last mentioned switch except when said first mentioned switches are all in "off" position.

11. In combination, a plurality of controlling drums, one or more motors under the control of each of said drums, a switch arranged to connect said drums and the motors controlled thereby in series and in parallel 115 and to cut out any drum and its associated motor or motors.

12. In combination, a plurality of controlling drums, one or more motors under the control of each of said drums, a switch ar- 120

- 5 ranged to connect said drums and the motors controlled thereby in series and in parallel and to cut out any drum and its associated motor or motors, and interlocking mechanism for preventing movement of said switch except when the drums are in "off" position.
13. In combination, a plurality of series-parallel regulating switches, a plurality of motors under the control of each of said switches and arranged to be connected in series and in parallel thereby, and another switch arranged to connect said first mentioned switches and their associated motors in series and in parallel.
14. In combination, a plurality of series-parallel regulating switches, a plurality of motors under the control of each of said switches and arranged to be connected in series and in parallel thereby, another switch arranged to connect first mentioned switches and their associated motors in series and in parallel, and interlocking mechanism for preventing movement of said last mentioned switch save when the first mentioned switches are all in "off" position.
15. In combination, a plurality of series-parallel regulating switches, a plurality of motors under the control of each of said switches and arranged to be connected in series and in parallel thereby, and another switch arranged to connect said first mentioned switches and their associated motors in series and in parallel and to cut out any one of said first mentioned switches and its associated motors.
16. In combination, a plurality of series-parallel regulating switches, a plurality of motors under the control of each of said switches and arranged to be connected in series and in parallel thereby, another switch arranged to connect said first mentioned switches and their associated motors in series and in parallel and to cut out any one of said first mentioned switches and its associated motors, and interlocking mechanism for preventing movement of said last mentioned switches save when the first mentioned switches are all in "off" position.
17. In combination, a plurality of series-parallel controlling drums, a plurality of motors under the control of each of said drums and arranged to be connected in series and in parallel thereby, and a switch arranged to connect said drums and their associated motors in series or in parallel.
18. In combination, a plurality of series-parallel controlling drums, a plurality of mo-
- 60 tors under the control of each of said drums and arranged to be connected in series and in parallel thereby, a switch arranged to connect said drums and their associated motors in series and in parallel, and interlocking mechanism for preventing movement of said switch save when the drums are in "off" position.
- 65 19. In combination, a plurality of series-parallel controlling drums, a plurality of motors under the control of each of said drums and arranged to be connected in series and in parallel thereby, and a switch arranged to connect said drums and their associated motors in series and in parallel and to cut out any one of said drums and its associated motors.
- 70 20. In combination, a plurality of series-parallel controlling drums, a plurality of motors under the control of each of said drums and arranged to be connected in series and in parallel thereby, a switch arranged to connect said drums and their associated motors in series and in parallel and to cut out any one of said drums and its associated motors, and interlocking mechanism for preventing movement of said switch save when the drums are in "off" position.
- 75 80 85 21. In combination, a plurality of regulating switches, one or more motors under the control of each of said switches, another switch arranged to connect first mentioned switches and their associated motors in series or in parallel, and to cut out any one of said switches and its associated motor or motors, and stops for preventing the movement of said last mentioned switch to any of its cutting-out positions unless the handle thereof is moved out of its normal plane.
- 90 95 22. In combination, a plurality of drums connected to operate together, each drum being arranged to control one or more motors, and a switch arranged to connect said drums and their associated motors in series or in parallel, and to cut out any drum and its associated motor or motors, and means for preventing the movement of said switch into any of its cutting out positions unless the handle thereof is first moved out of its usual plane.

In testimony whereof I affix my signature, in the presence of two witnesses.
